UNITED STATES PATENT OFFICE.

JAN KUCINSKI, OF CHICAGO, ILLINOIS.

CHILD'S VEHICLE.

1,379,993.

Specification of Letters Patent. Patented May 31, 1921.

Application filed June 16, 1920. Serial No. 389,275.

To all whom it may concern:

Be it known that I, JAN KUCINSKI, a citizen of Poland, residing at Chicago, county of Cook, and State of Illinois, have invented certain new and useful Improvements in Children's Vehicles, of which the following is a specification.

This invention relates to toys, and the object of this invention is to provide a toy suitable for children and one which is instructive as well as particularly interesting and amusing.

Referring to the drawings,—

Figure 1 is a sectional side view of the 15 toy on the line 1—1 of Fig. 2.

Fig. 2 is a plan view.

Fig. 3 is a front view with part of the front plate removed.

Figs. 4 and 5 show certain parts of the 20 invention in perspective, and

Fig. 6 is a side view.

Similar reference characters refer to similar parts throughout the several views, and in which—

25 A toy wagon-like structure, comprising a floor member 1, front member 2, rear member 3, side members 4 and 5, central member 6, and seat member 7, rear axle 8, front axle 9, wheels 10 on axle 8 and wheels 11 on axle 30 9, is shown, the parts being fastened together in any suitable manner permitting of wheels 11 to revolve whenever the toy is propelled backward or forward. The ends of shaft 9 are shown square and nested in 35 similar sized perforations in wheels 11, as at 12, and near the center of the shaft is mounted, by gluing or other suitable means, a gear wheel 13 in mesh with another gear wheel 14 fixed to a shaft 15 rotatably carried in supports 16 and 17 mounted on floor member 1, said shaft 15 having also fixed thereto a pulley wheel 18 and a pair of crank arms 19 and 20. Two lever arms 21 and 22 are shown pivoted on a rod 23 supported by supporting members 24 and 25 carried on floor member 1, and these lever arms are connected to crank arms 19 and 20 by means of links 26 and 27, so that lever arms will be moved back and forth upon ro-

tation of shaft 15. On floor member 1 near 50 the rear end thereof are mounted a pair of supports 28 and 29 supporting a rotatable shaft 30 on which is fixed a pulley wheel 31 and a pair of crank handles 32 and 33, wheel 31 being belted by means of a string 55 or tape 34 to wheel 18.

It is evident from the above that when wheels 11 are turned as by movement of the toy backward or forward, shaft 9 will rotate causing gears 13 and 14 and shaft 15 to 60 rotate, thus effecting reciprocating movement of lever arms 21 and 22 and a turning of wheel 31 and crank handles 32 and 33.

It is possible to construct this toy large and substantial enough to carry a child 65 and, in this event the toy may be propelled by the child either by turning crank handle 32 or 33, or by reciprocating lever arms 21 or 22.

A toy of the construction above described 70 is of unusual interest to a child on account of the many and varied movements of the parts and is particularly instructive in that the toy illustrates so many and varied mechanical movements and means of power 75 transmission.

Having thus described my invention what I claim as new and desire to secure by Letters Patent of the United States, is—

In a toy, in combination, a wagon-like 80 structure having a pair of wheels mounted on and revoluble with an axle thereon, a gear on said axle, a rotatable shaft mounted on said structure, a second gear fixed to said shaft and meshing with said first gear, a 85 pulley wheel on said shaft, a second pulley wheel mounted on said structure and in driving connection with said first pulley wheel, a pair of crank arms on said shaft, and a pair of pivoted lever arms mounted on 90 said structure, each lever arm being linked to one of said crank arms, whereby upon rotation of said first wheels said lever arms will be reciprocated and both of said pulley wheels will be caused to turn. 95

In testimony whereof I have affixed my signature.

JAN KUCINSKI.
